UNITED STATES PATENT OFFICE

SAMUEL GALLAGHER, OF NEW YORK, N. Y.

CHUTE FOR WASTE BUILDING MATERIAL

Application filed October 31, 1930. Serial No. 492,572.

This invention relates to improvements in chutes and has particular reference to a chute which may be erected upon buildings undergoing construction or demolition into which waste material may be deposited for accumulation in a pile at the bottom thereof, or for loading upon a truck or other conveyance which may be positioned beneath the bottom of the chute.

10 The principal feature of the invention is to construct a chute of a plurality of separate units arranged one upon the other and which are of a length approximating the distance between two of the floors of a building, there being means for securing the units in position so that they produce a continuous enclosed chute for any number of consecutive floors which it is to serve.

Another object is to provide a chute which 20 is constructed of a plurality of separate foldable units in order to facilitate the transporting of the device from place to place or from one building operation to another.

A further object is the provision of a chute 25 constructed of a plurality of units, each unit including a plurality of hingedly connected side walls to enable the same to be folded flat when not in use whereby the units may be easily handled and compactly stacked or stored.

A further object is to provide a chute constructed of a plurality of metal units to 30 reduce the fire hazard present in wooden style chutes and which is sometimes caused by the friction of the materials passing through the chute.

With these and other objects in view, the 35 invention resides in the certain novel construction, combination and arrangement of parts, the essential features of which are hereinafter fully described, are particularly pointed out in the appended claims, and are illustrated in the accompanying drawings, in which:

Figure 1 is a front elevational view of a 40 building structure showing my improved chute in erected position thereon.

Figure 2 is a perspective view of one of the 45 chute units per se.

Figure 3 is a plan view of one of the chute units in a partially folded condition.

Figure 4 is an enlarged vertical transverse sectional view on the line 4—4 of Figure 1.

Figure 5 is a horizontal sectional view on 55 the line 5—5 of Figure 4.

Figure 6 is an enlarged detail horizontal view on the line 6—6 of Figure 4.

Referring to the drawings by reference characters, the letter A designates a building 60 of any number of stories and is provided with a window opening B at each floor thereof, the said window openings being in vertical alignment as is the custom in tall building structures. My improved chute is shown in its 65 entirety in Figure 1 and is constructed of a plurality of chute units 10, the same being of equal length approximating the distance between the floors of the building structure. The chute units 10 are of identical construction with the exception of the lowermost or bottom unit, but which latter unit only differs from the others in a manner to be presently explained.

Each of the units 10 is open throughout 70 its length and is constructed of opposed side walls 11—11, a front wall 12, and a back or rear wall 13. The side edges of the front wall 12 and rear wall 13 are connected to the side edges of the side wall 11 by hinges 75 14 whereby the said walls may be folded or collapsed into a flat condition when the chute is not in use to enable handling and storing of the units. Figure 3 shows one of the units 80 in a partially folded condition, but it will be understood that the folded walls will lie 85 one against the other so as to be compact.

The rear wall 13 is provided with an opening 15 which extends the width of the back wall and which opening is adapted to register 90 with a window opening B when the unit is in an erected position. Attaching plates 16 are fixed to the opposed side walls 11 and extend beyond the rear wall 13 for a purpose now to be explained.

When a unit 11 is positioned with respect to one of the window openings, the wings or attaching plates 16 extend through the window openings adjacent the side walls thereof and which are secured to anchor rods 17, 100

there being two rods connected to each of the attaching plates, or a total of four rods for the anchoring of one of the chute units in position. The opposite ends of the anchor rods 17 are screw threaded as at 18 to threadedly receive clamping heads 19, the same being provided with an internally threaded socket to receive the threaded end 18 and a base or flanged portion for bearing engagement with the opposed walls of the window opening B. By threadedly connecting the clamping heads 19 to the rods, the rods may be fitted into windows of varying heights, and by turning the rod relative to the clamping head, the said head may be forced into clamping engagement with the opposed wall of the window opening. After the rods have been secured in position, the wings or attaching plates 16 are secured thereto by fastening elements 20 which in the present instance are shown as bolts which pass through openings 21 provided in the attaching plate, and which register with openings 22 extending through the rod 17, and the said bolt being held secure by nuts 23. It will therefore be seen that when the respective chute units are secured in position to the rods 17 mounted in the respective window openings, the said sections will be securely anchored in position one upon the other to produce a continuous chute extending from one floor to the next and which extends downward to the ground, the lowermost unit 10 being provided with an outlet 24 in the front wall to permit of the removal of the waste material from the chute, or to enable a truck to be backed in position so as to receive the waste material as it passes down the chute.

As previously stated, the opening 15 in the back wall of each unit registers with one of the window openings to enable waste material from the various floors to be deposited into the chute direct from a wheelbarrow or other carrier and the attaching plates 16 serve to prevent the accidental spilling of the material between the chute and the building structure during the deposit of materials into the chute.

From the foregoing description, it will be seen that I have provided a waste material chute which may be erected for use upon a building during construction or demolition thereof and after serving one job, it may be taken down and collapsed and transported to another building operation. It will be appreciated that at present it is customary to construct such chute of wood which is demolished after serving its purpose on a building operation. The life of a chute such as shown and described is unlimited, and should any of the units become broken or worn, they may be readily replaced by new ones. The units are easy to handle and erect so that much time is saved in the erection of a chute than required for the construction of the

present wooden type. Furthermore, the metal chute is fire proof and greatly reduces the fire hazard now caused by friction of the waste material in their passage down the chute.

While I have shown and described what I deem to be the most desirable embodiment of my invention, I wish it to be understood that various changes in construction may be resorted to if desired, and I do not limit myself to the precise structural details herein set forth, nor to anything less than the whole of my invention limited only by the appended claim.

Having thus described the invention, what I claim as new and desire to secure by Letters Patent is:—

In a structure for removing waste building material from buildings having windows, a chute comprising a plurality of substantially rectangular sections arranged in end to end relation and each section having side and inner and outer walls, the inner wall being provided with an opening registering with one of the windows for waste building material, and plates attached rigidly to said side walls and located at the ends of said opening, and means hingedly joining the side walls to said front and rear walls to permit collapsing of the chute section, said plates being provided with means at greatly spaced points by which the plates may be secured rigidly within a window opening to hold the chute in an open position.

In testimony whereof I affix my signature.

SAMUEL GALLAGHER.
